UNITED STATES PATENT OFFICE

ALBERT VICTOR RAYMOND, OF GRENOBLE, FRANCE

SLIDER OPERATING CLOSURES

Application filed August 25, 1931, Serial No. 559,307, and in France August 28, 1930.

The present invention relates to improvements in the type of closures consisting of two flexible strips or bands (of tissue, cloth or other materials) which are provided with 5 rows of fastening elements adapted to be interlocked by means of a slider, this slider being able to slide freely along said flexible strips.

These strips or ribbons are generally connected at one of their ends by a fixed tie and it is therefore impossible to wholly remove one of them from the other, when operating the slider for unlocking.

This feature is of great disadvantage for 15 many uses, when a complete separation of the strips or bands is absolutely required. If the separation and reconnection of the strips with their interlocking fastening elements could be easily effected, these slider-operating closures would find important new applications for many goods, personal wears, etc.

One of the objects of my invention is to provide a new and improved device for closures of said type, which enables to wholly 25 remove one of the interlocking strips from the other, each of these separated strips always keeping its row of fastening elements.

A further object is to provide a new device which enables to easily reconnect the 30 two separated strips with their interlocking elements by joining their edges at their extremity.

According to my invention, the said device consists essentially in a guide member, for instance a metallic one, to be fixed on 35 one of the strips, said member enclosing and retaining, when both strips are connected, two tubular rigid members fixed to the end of each strip, for the purpose of joining said strips together at their extremities.

This guide member is so devised as to allow the slider to penetrate thereinto, and elastic means, preferably including a sliding member and a spring, are adapted to cooperate with said guide member in such manner

as normally to prevent the slider from moving as far as the end of the two rows of interlocking fastening elements, so that said last elements remain interlocked. However 50 said elastic means are adapted to yield to an increased effort so that the slider may move further and separate the last interlocking elements. It is then possible to remove one of the tubular rigid members from the guide member and thus to separate the two strips. 55

In order that my invention may be fully understood it will first be described with reference to the accompanying drawings and afterwards more particularly pointed out in the annexed claims, my invention being not 60 particularly directed to or limited to any special type of fastening members.

In the accompanying drawings, wherein is shown a preferred embodiment of my invention:

Figs. 1 to 3 show the device according to the invention, the last fastening elements being still interlocked.

Fig. 1 is a front view of said device mounted on the end of both closing strips. 70

Fig. 2 is a section on the line 2—2 of Fig. 1.

Fig. 3 is a section along the line 3—3 of Fig. 1.

Figs. 4 and 5 show the same device after 75 the slider has been brought at the extreme point of its stroke, thus unlocking the last fastening elements.

Fig. 4 is a front view.

Fig. 5 is a sectional side view on the line 80 5—5 of Fig. 4.

Fig. 6 is a detail view showing in perspective one of the parts of the device according to my invention.

As shown in the drawings, two metallic 85 tubular members *c* are secured, along a predetermined length to the edge of the extremity of each strip *a* and *b*, said strips carrying in a known manner the fastening elements *a*, *b*, which can be separated and refastened 90

by means of the slider *j* with its operating piece *j*₁.

5 A guide member *d*, preferably made up of a metal sheet, is fixed at the end of one of the strips, for instance at the extremity of the strip *b* (Fig. 1).

10 Said guide member surrounds the metallic tubular member *c* that corresponds to strip *b* and is adapted to slidably receive the metallic tubular member *c* of strip *a*, so that said members *c* are disposed side by side in guide member *d*.

15 A socket *e* can slide inside guide member *d*. As shown in the detail view of Fig. 6, said socket consists of a prismatic structure, open at the top and provided with a flange 2, and the bottom of which is provided with openings for members *c*. Said socket is slidably mounted in guide member *d* in such manner 20 that its upward motion therein is limited by flange 2 butting against the top of said guide member.

25 A spiral spring *f*, fitted in guide member *d* and bearing upon the bottom of said guide member, is adapted to act upon said flange 2 so as to constantly tend to maintain socket *e* in its upper position inside guide member *d*, by applying said flange 2 against the under side of the top of said guide member.

30 To wholly disengage the strips, the successive operations will be as follows:

35 The fastening elements are unlocked by operating the slider *j* to ride until it knocks against the edge *h* of the socket *e* (Figs. 1 and 2); then, the slider is further operated in such manner that it draws down the socket *e* to the bottom of the guide member *d*, thus compressing the spring *f* and unlocking the last fastening elements *g*. (Figs. 4 and 5).

40 Keeping then the slider in this position, one can easily take off the flexible strip *a* in the direction of the arrow *F* for wholly removing it from the guide member *d* and then from the slider *j*.

45 When the reconnection of the extremities of the strips is desired, the same operations are effected in the reversed way: the socket *e* is drawn down to the bottom of the guide member *d* by operating the slider *j*, and thereafter the end of the strip *a* is introduced into the channel of the slider and carefully engaged to the bottom of the guide member. By releasing then the slider, said slider is drawn upwards by the socket *e* under the 55 action of the spring *f*. The first fastening elements are thus interlocked and it only remains to draw the slider to its closing position.

60 What I claim is:—

65 1. In a separable fastener including two flexible strips of flexible material each carrying a row of fastening elements adapted to be interlocked and unlocked by means of a slider, an end closure comprising in combination, a guide member secured to the end of

one of said strips and adapted to slidably receive the end of the edge of the other strip, and elastic stopping means adapted to cooperate with said guide member for normally preventing the slider from moving as far as the end of the two rows of fastening elements, so that the last elements of said rows normally remain interlocked, said elastic stopping means being adapted to yield to an increased effort exerted on the slider, so that said last elements of the two rows may then be disengaged from each other, and the strips fully separated.

70 2. In a separable fastener including two flexible strips of flexible material each carrying a row of fastening elements adapted to be interlocked and unlocked by means of a slider, an end closure comprising in combination, a tubular metallic member fixed to the end of the edge of each of said strips, a guide member secured to the end of one of said strips surrounding the tubular member fixed to said strip and adapted to slidably receive the other tubular member, so that said tubular members may be disposed side by side in said guide member, and elastic stopping means adapted to cooperate with said guide member for normally preventing the slider from moving as far as the end of the two rows of fastening elements, so that the last elements of said rows normally remain interlocked, said elastic stopping means being adapted to yield to an increased effort exerted on the slider so that said last elements of the two rows may then be disengaged from one another, and the last mentioned tubular element removed from the guide member.

75 3. In a separable fastener including two flexible strips of flexible material each carrying a row of fastening elements adapted to be interlocked and unlocked by means of a slider, an end closure comprising in combination, a tubular metallic member fixed to the end of the edge of each of said strips, a guide member secured to the end of one of said strips, surrounding the tubular member fixed to said strip and adapted to slidably receive the other tubular member, so that said tubular members may be disposed side by side in said guide member, a socket adapted to slide in said guide member, the upper edge of said socket being adapted to engage the corresponding edge of said slider, a spring for applying said socket against the top of said guide member, for normally preventing said slider from moving as far as the ends of the two rows of fastening elements, so that the last elements of the rows normally remain interlocked, said spring being adapted to yield to an increased effort exerted on the slider so that said last elements of the two rows may then be disengaged from one another and the last mentioned tubular element removed from the guide member.

4. An end closure according to claim 3 in which the guide member is so made as to allow the slider to penetrate thereinto.

5. An end closure according to claim 3 in which the socket is provided with two holes for the metallic tubular elements, a flange on said socket adapted to abut against the top of said guide member, the spring being a spiral spring interposed between the bottom 10 of said guide member and said flange.

In testimony whereof I have signed this specification.

ALBERT VICTOR RAYMOND.
